UNITED STATES PATENT OFFICE

JOSEPH C. WHITE, OF BOSTON, MASSACHUSETTS, ASSIGNEE, BY MESNE ASSIGNMENTS,
TO WHITE AUTOMATIC GUN CORPORATION, OF PORTLAND, MAINE, A CORPORATION
OF MAINE

AUTOMATIC GUN

Application filed January 8, 1930. Serial No. 419,316.

My invention relates to guns, more particularly to semi-automatic rifles adapted to be fired from the shoulder, and aims to provide a simplified, compact, rugged but light-weight, and otherwise improved mechanism of the class described. While certain features of the invention relate especially to semi-automatic guns, that is, self-loading single-fire devices, other features are equally useful in connection either with hand-operated or with full automatic weapons, including machine guns. As to certain common features this application constitutes a refiling of my prior applications Serial No. 46,882, filed August 23, 1915, and renewed as Renewal Serial No. 492,635 on August 15, 1921; Serial No. 255,787, filed September 26, 1918; and Serial No. 476,983, filed June 13, 1921.

In the drawings illustrating one embodiment of the invention, by way of example, Fig. 1 is a left side elevation of a completely assembled rifle of the gas-operated type;

Fig. 2 is a vertical longitudinal section through the receiver, breech closure and associated parts;

Fig. 3 is a view similar to Fig. 2 but with the breech open, the feed mechanism being omitted for the sake of clearness;

Figs. 4 and 5 are vertical cross-sections respectively on the lines 4-4 and 5-5 of Fig. 2;

Fig. 6 is a vertical cross-section on the line 6-6 of Fig. 3;

Fig. 7 is a horizontal longitudinal section on the line 7-7 of Fig. 2;

Fig. 8 is a plan of the receiver alone;

Fig. 9 is a vertical longitudinal section on the line 9-9 of Fig. 8;

Figs. 10 and 11 are vertical cross-sections on the lines 10-10 and 11-11 respectively of Fig. 9;

Fig. 12 is an exploded perspective view of the breech closure assembly including the block proper, the action plates, the extractor and the extractor spring;

Fig. 13 illustrates a portion of the firing mechanism in elevation, including the striker, sear and safety devices;

Fig. 14 is a horizontal longitudinal section on the line 14-14 of Fig. 3, looking down;

Fig. 15 is a detail view of the striker spring and striker spring carrier; 55

Fig. 16 is a perspective of an element of the firing mechanism, herein termed the disconnector, mechanically intermediate the trigger and the sear;

Fig. 17 is a vertical transverse sectional view, looking forwardly, showing the safety device; 60

Fig. 18 is a plan of the rear portion of the actuator, slide, or gas fork;

Figs. 19 and 20 are longitudinal, central, vertical sections substantially in continuation of each other, through the barrel and gas mechanism; 65

Fig. 21 is a front view of a cartridge loader, clip or packet; 70

Fig. 22 is a section on the line 22-22 of Fig. 21;

Fig. 23 is a plan of the combined follower-spring and packet-ejecting spring;

Fig. 24 is a cross-sectional detail showing a release for use in removal of a cartridge loader or packet while still full or partly so; and 75

Fig. 25 is a detail showing the mounting of the ejector and the packet catch. 80

In the illustrative construction of the drawings, referring first to Fig. 1, the barrel is indicated at 1, the receiver or frame at 2, and the stock at 3, the latter in this instance including a pistol grip 4 and butt 5. A separate-piece forestock or barrel-cover 6 is shown, abutting the receiver and held by a strap 7 which serves also as a base for the shoulder-strap ring 8; this forestock may be omitted if desired. 85

The barrel is threadedly connected to the receiver, as by means of a barrel-bushing 9 which adapts the receiver for use with different barrels; see also Fig. 2, 3 and 7. The fore-part of the receiver has a depending lug 10 tapped to receive the screw 11 by which the stock and receiver are secured together. Removal of this single screw, and of the strap 7 permits the barrel and receiver to be dismounted from the stock. 100

While numerous features of the invention are applicable to firearms or ordnance in general, whether recoil, gas or otherwise operated, my invention includes the provision of novel gas-operating mechanism.

Gas mechanism

Referring now to Figs. 19 and 20, the barrel is provided with a gas-port 12, herein near the muzzle end. A port-housing 13 is fitted and pinned to the barrel and is bored to receive a gas-tube or supplementary chamber 14, the latter and the port-housing 13 having ports in registry with the barrel-port 12. The gas tube is further supported in a collar 15 depending from a sleeve 16 surrounding and pinned to the barrel and carrying the base 17 for the front sight 18. The forward portion of the gas tube is of larger external diameter, providing a shoulder 19 which abuts the collar 15. The front end of the gas tube is closed by a screw-plug 20 having a collar portion 21 surrounding and fitted to the barrel. The barrel is preferably provided with one or more upwardly directed ports 22, herein in the plane of said collar portion 21, the latter being ported in radial line with the barrel ports, whereby a portion of the gas is released upwardly, counteracting any tendency of the muzzle to "climb". As illustrated, the barrel terminates in a muzzle nut 23 having a series of radially disposed vents 24, whereby additional gas is released to atmosphere prior to the exit of the bullet from the barrel. I find in actual practice that such provision materially lessens the recoil.

Slidable in the gas tube 14 is a hollow piston 25, open forwardly but closed at its rear end. A series of annular round-bottomed grooves 26 may be cut in the outer surface of the piston, to facilitate its sliding action and to act as gas baffles. The rear wall of the piston 25 abuts the front wall of the action-spring housing or tube 27, the rear end of which is threaded into the breech-actuator, action slide or gas fork 28; see also Fig. 18. The spring housing constitutes in effect the forward portion of said action slide. The piston 25 and the action-spring tube 27 are mechanically but separably connected by a lug 29 on a projection at the rear of the piston, received in a slot in the spring tube. The action-spring 30 is confined between the front wall of its housing or tube 27 and an annular shoulder 31 on the spring guide-rod 32, the rear end of which is slidable in the lug 10 on the receiver, see also Figs. 2 and 3, but is held against rearward movement by a shouldered portion 33 abutting said receiver lug. The sliding spring tube 27 is guided in a bearing 34, Fig. 20, depending from a collar 35 pinned on the barrel.

In Fig. 19 the piston is shown in full lines

in its normal or forward position, while its full rear position is indicated in dotted lines. It will be noted that the gas tube 14 has a rearwardly extending lip or port cover 14a which does not uncover the gas-port 25a of the piston until the latter approaches the rear of its stroke.

In the illustrated embodiment I have shown a relatively small and short barrel-port in combination with a ported piston having a relatively large gas-storage and expansion chamber, the piston port 25a being located intermediate the ends of the chamber.

In operation, when a bullet has passed the barrel-port 12, high-pressure live gas enters the piston 25 through this port, the port in the gas tube 14, and the then registering port 25a in the piston. As the gas in the piston reaches a pressure sufficient to overcome the resistance of the action-spring 30 and the reciprocating parts, the piston moves rearwardly, closing the barrel-port. The gas is thus trapped in the piston and the gas tube, where it expands, actively, causing a continued smooth rearward movement of the piston. This steady expansive action of the gas continues throughout the major portion of the action stroke of the piston and connected parts. Before the full travel of the piston has taken place, however, the piston port 25a passes beyond the port-cover 14a of the gas tube, and is uncovered. A large and sudden drop of gas pressure therefore occurs, with resultant slowing down of the piston.

On the reaction or forward stroke of the piston, effected by the expansion of the action spring which was compressed during rearward travel of the piston, the air and any remaining gas in the gas-tube are compressed, thus cushioning the rapid reaction stroke of the parts, until the piston port again registers with the barrel-port 12, when the compressed air and spent gas in the tube escape into the barrel, serving to cool the bore and to drive out any residue.

The described gas-mechanism affords a safe and positive means for operating the breech-closure, particularly one of the extreme lightness as herein disclosed. The gas is utilized expansively rather than by way of a violent initial impulse or hammer-like blow characteristic of known gas systems employing a free or continuously open port 25a. The parts are caused to move back under control rather than to be blown back by the initial gas impulse. By the described means I trap in the piston or expansion chamber a quantity of live, expanding gas sufficient, at its initial pressure, to over-balance the variable resistance to the breech opening effort, and at its final pressure adequate to have completed the rearward stroke of the piston and other reciprocating parts. By thus con-

trolling the admission of gas from the barrel, automatically taking a load-compensating quantity, irrespective of variations in such load or resistance to breech-opening effort, I 5 avoid the chief objections of the usual open-port system, the violent and premature breech-opening effort, or the necessity of heavy reciprocating parts to store enough energy from a violent initial gas impulse to 10 complete the full stroke after the pressure has dropped.

It will be understood that the described piston, in functioning to drive the breech mechanism, controls the inflow and outflow 15 of gas, on the rearward stroke, and acts as a reducing valve to check the piston speed as it approaches the limit of its rearward travel. On the return or forward stroke it traps and compresses air, checking the forward 20 speed and affording adequate time for cartridge feed, reducing the likelihood of jamming and of abrasions on the shoulder of the cartridge case. The compressed air charge, being released only through the barrel port, serves to scavenge and cool the bore.

The compensating action of the described gas mechanism provides for proper, uniform breech action despite variations not only in 30 the resistance to breech-opening effort but also in explosion-chamber pressures. If greater opening effort is needed, more gas is automatically taken. If abnormally high gas pressures are developed, the inflow of gas 35 is automatically more quickly cut off and less gas is taken. Full functioning of the mechanism may be obtained with chamber pressures varying as widely as between 20,000 pounds below and 20,000 pounds above that 40 of standard army ammunition.

Action-slide and breech closure

The action-slide or gas fork 28 is shown separately, in plan, in Fig. 18. It is indicated in dotted lines in Fig. 1, and may be seen respectively in forward and in retracted positions in Figs. 2 and 3, while cross-sections are shown in Figs. 4 and 5 and a rear view in Fig. 6. At its forward end is 50 the threaded collar portion 36, in which the spring housing or tube 27 is secured. Rearwardly of this collar portion is the slide or fork proper 28, of elongated saddle-like form, somewhat narrower at its fore-part 55 and with its two slide or fork portions spaced transversely to straddle the feed and firing mechanisms, and to lie below and in vertical alignment with the opposite side walls of the receiver 2. The gas-fork or 60 actuator, as well as the entire gas mechanism already described, is centrally disposed below the barrel, affording complete lateral balance. It is substantially completely concealed by the receiver and stock, leaving no 65 working part exposed.

On the rear of each fork of the actuator 28 is an upwardly and inwardly extending lug 37 (see particularly Figs. 3, 5 and 18) each having a beveled outer face 38 and above it a lateral rib 39. These ribs 39 work 70 in corresponding grooves 40, 40 (see Figs. 9 and 11) on the inner walls of the receiver 2, while the beveled faces 38 bear against similar surfaces 41, 41 on the receiver walls. The main, inwardly projecting portion of 75 each actuator lug 37 is received in a similarly shaped recess 42 in one of the action-plates 43 at the sides of the breech-lock, bolt or closure proper 44, now to be described.

The breech-lock and action-plate assembly is seen in Figs. 2, 3, 4, 6 and 7, and in detail in Fig. 12. As best seen in said Fig. 12, the action-plates 43, just mentioned, are of inverted L-shape in section, having lateral ribs 80 45 at their upper edges. Their rear ends abut the lateral shoulders 46, 46 at the rear of the block when the latter is in elevated position, that is, when its top face is in the plane of the top faces of the action-plates. 85

These action-plates have only a lengthwise reciprocating movement in and upon the receiver, their lateral ribs 45 being guided in such movement in the way portions 47, 47a at the opposite sides of the receiver, 90 Figs. 9, 10 and 11, and along and upon the top of the receiver at points intermediate or rearwardly of said way portions or ways.

The straight-line reciprocation which is imparted to the action-plates 43 by the actuator 28, through the lugs 37 of the latter, transmits both a longitudinal opening and closing movement and a vertical locking and unlocking movement to the block 44. This is effected by means of one or more, 100 herein two, block-engaging ribs 48, 48 on the inner faces of the action-plates and extending forwardly and upwardly at angles 45° with respect to the block axis and the axis of the bore. These ribs are received 105 in correspondingly shaped and arranged action slots 49, 49, etc. in the side faces of the block.

The block 44, as best seen in Fig. 12, is a straight-line, reciprocating, non-rotary element having, in its closing action, a final vertical positive-locking movement and a corresponding vertical unlocking or preliminary movement before it moves back from the firing position in which it is shown in 110 Fig. 2. It is a symmetrical, balanced element, rectilinear and preferably of one piece of metal, with a minimum of material cut away. At its forward end is a plurality 115 of symmetrically disposed locking lugs, an upper pair 50, 50 and a lower pair 51, 51 all equally spaced from the block axis. Each lug is of relatively large cross-sectional area, these lugs together providing a total locking surface approximately double that re- 120 125 130

quired for any pressure likely to be developed in service. It will be noted, see particularly Fig. 12, that the action plates are in line with the locking lugs at the head of the block but that they are somewhat less in length than the distance between those locking lugs and shoulders 46 at the rear of the block, permitting a limited relative movement between the plates and the block.

10 The block locking lugs cooperate with correspondingly disposed locking abutments, an upper pair 52, 52 and a lower pair 53, 53, on the inner walls of the fore part of the receiver, just behind the explosion chamber; Figs. 7, 9 and 10.

15 Assume now that the breech closure is open, in full retracted position as in Fig. 3, the action spring being compressed, the closing and locking action is effected as follows: the re-expanding action spring, having a fixed rearward bearing against the receiver lug 10, acts forwardly against the fore end of the spring housing or tube 27 to move it and the entire action slide or gas-fork 28 forwardly. Through the actuator lugs 37 of the latter, the action-plates 43 are moved forwardly, carrying with them the breech block 44, through the engagement therewith of the inclined ribs 48 on the plates. During this closing movement the upper locking lugs 50 of the breech block and the lateral ribs 45 of the action-plates are on the same level, both being guided in the receiver ways 47 and 47a.

20 25 Before the action-slide reaches its full forward position, the head of the block brings up against the barrel. The action-plates, however, are free to continue forwardly, now moving relatively to the block, under the action of the final forward movement of the slide. By reason of the 45° inclined rib and groove connection between the action-plates and the block, this final relative movement of the action-plates cams the block downwardly until its upper locking lugs 50, 50 lie in front of the receiver abutments 52, 52 and its lower locking lugs are in front of the lower receiver abutments 53, 53.

30 35 The breech closure is thus positively locked in firing position, as seen in Figs. 2 and 7. The fore ends of the action-plates at such time remain back of and out of contact with any part of the head of the block, so that no direct force of the explosion is received by them, but is transmitted entirely to the receiver, through the several locking lugs of the block and the receiver abutments with which the latter are then in line.

40 45 The unlocking and opening movements of the breech take place in reverse sequence to that described. When a cartridge has been fired and a sufficient gas pressure has been built-up in the piston to overbalance the resistance of the action-spring and other re-

sistance to the breech-opening effort, the piston and slide or gas-fork move back, taking the action-plates 43 with them. During the first of the rearward movement of the latter, the block is restrained from movement to the rear, by the receiver abutments, and consequently its inclined rib and groove connection with the action plates must move it vertically, upwardly, across the head of the shell, until its locking lugs clear the receiver abutments, and the upper pair of lugs come into line with the receiver ways 47, 47a. Not until then is the block unlocked and free to open under the continuing gas-impelled back movement of the action-slide.

50 55 The gas-impelled movement of the action-slide and breech-block is suitably arrested, preferably by a buffer similar in principle to that of my Patent No. 1,410,436, dated March 21, 1922 and within the broad scope 60 of claims of that patent. This buffer, as herein shown, consists of a single element 55 of heavy spring metal secured flat-wise against the lower face of the rear cross piece 2a of the receiver, as by screws; see 65 Figs. 2, 3 and 7. Its forward edge 56 is bevelled off at an angle of approximately 45°, for engagement with similarly angled 70 abutment surfaces 57, 57 on the rear of the two forks of the gas-fork or actuator. When 75 engaged by the gas-fork this buffer yields transversely of the receiver, herein downwardly, giving an extremely effective shock-absorbing action.

80 85 Referring again to the breech block, and particularly to Fig. 12, it will be seen that the breech locking lugs 50, 50, 51, 51 extend forwardly of the actual closure face 58 of the block, affording sufficient head-space to accommodate such variations in cartridge 90 length as inevitably are met in service ammunition. A lip 59 at the lower portion of the block face and having a curved upper surface provides a bottom seat for the head of a cartridge during the feeding and the 95 extracting operations; see also Figs. 2 and 3. This lip is interrupted by the ejector slot 60 in the under face of the block head, for passage across the ejector, to be described.

100

105

110

115

Extractor; firing pin; ejector

120 Extraction of a shell is effected automatically with the opening of the breech closure, by an extractor, indicated as a whole by the numeral 61, Fig. 12. It comprises a top piece 62 downwardly and inwardly beveled at its sides, to seat in a like bevel-sided recess 63 in the top face of the breech block head. A toe 64 depends at the fore end of the top piece 62, having side ribs 65, 65, which fit, somewhat loosely, in vertical ways 66, 66 in the inner faces of the projecting portions of the block locking lugs 50, 50. The toe terminates in a depending arcuate lip 67 125

130

adapted to fit over the rim of a shell and into the channelure thereof; see Figs. 2 and 3. This lip 67 extends but part way across the extractor, from the right of the gun (the 5 left side as viewed in Fig. 12) ending short of the vertical plane of the ejector slot 60. Thus the shell rim is engaged by the extractor at a portion above and mainly to the right of its center line, and is engaged by 10 the ejector at a point below and to the left of its center line, whereby the extracted shell is ejected upwardly, to the right, and forwardly.

The ejector is seen at 68 in Figs. 2 and 3, 15 being an upright tapered member of heavy spring material having a right-angled base 69 whereby it is secured to the guard plate 70.

Referring again to the extractor 61, Fig. 20 12, there extend back from the top-piece 62, at opposite sides of the breech block, a pair of fingers 71, 71 ending in upward nubs 72, 72. These fingers are respectively received in grooves 73, 73 in the forward ends of the 25 side ribs 45, 45 of the action plates 43, 43.

The extractor is yieldably held in position by the extractor spring 74, an elongated flat member of suitable spring metal, resting upon the top of the block 44 and the action- 30 plates 43, 43 and constituting in effect a cover for substantially the entire breech closure assembly. At its front end the extractor spring is formed with the slightly depressed spring fingers 75, 75 which bear 35 upon the fore parts of the extractor fingers 71, 71 while the tongue portion 76 of the spring between these fingers straddles the rear of the top-piece 62 of the extractor. Thus the extractor is urged downwardly but

40 can ride up over the rim of the cartridge as the latter is engaged in the loading operation, the extractor lip 67 then snapping down into the cartridge channelure under the action of the extractor spring. In the form

45 illustrated this movement of the extractor is actually a slight vertical rocking action, permitted by the slight clearance between the extractor ribs 65, 65 and their ways 66, 66 in the block, the rear of the top-piece 62 50 of the extractor having in effect a pivotal bearing engagement with the front edge of the tongue 76 of the extractor spring. It will be noted that in the closed and locked position of the breech block, Fig. 2, the lat-

55 ter has moved down with respect to the extractor which remains at the level of the action-plates 43, still under control of its spring. It will also be observed that the 60 double finger construction of this spring provides in effect a double extractor spring, either portion alone being capable of operating the extractor.

At the rear of the extractor spring 74 are two downwardly projecting pins 77, 77 65 secured to the spring in any suitable manner

as by brazing them in two thicknesses of the spring material, formed by folding the end of the spring over upon itself. These pins are received in corresponding vertical holes 78, 78 in the block, and serve both to 70 position the extractor spring and, as seen in Figs. 2, 3 and 7, to retain the firing pin 80 in its channel 81 extending axially through the block.

The firing pin 80, as best seen in Fig. 7, 75 has a butt 82, adapted to be engaged by the striker, to be described in connection with the firing mechanism, this butt being received in a correspondingly sized enlarged portion at the rear of the channel 81 and being vertically slotted at 83, 83 for reception of the extractor-spring pins 77, 77. Forward movement of the firing pin is limited by the end wall 84 of said enlarged portion of the channel 81. The firing pin is 80 guided and centered in its channel, intermediate its ends, by the collar bearing 85.

Referring again to the receiver and breech-closure, and particularly Figs. 2, 9 and 11, the rear upper portion of the receiver is completely closed by the readily openable receiver-cap 87 pivoted at 88 between ears 89, 89 on the side walls of the receiver, see Fig. 11. This receiver cap is held closed by the receiver-cap latch 90 pivoted at 91 in 90 a slotted portion of the stock abutment or plate 92 and engaging a retaining lug 93 on the inner face of the receiver-cap, being urged toward that position by the latch spring 94. This latch is releasable when desired, by its concealed but readily accessible thumb-piece 95. The stock abutment 92 is itself anchored to the stock as by the screw 96 and the bolt 97, which extends up through the stock and through the guard-plate 70 95 and thus serves also to hold the rear of the latter in position.

From the foregoing it will be seen that the entire breech closure assembly, including the parts shown in Fig. 12 and the firing pin, can readily be removed as a unit, by merely opening the receiver-cap, the gas-fork 28 being held retracted in the manner to be described, and withdrawing this unit upwardly and rearwardly. The previously 100 described connection between the action-plates 43, 43 and the gas-fork, by means of the actuating lugs 37, 37, permits this ready dismounting of the breech block assembly.

With the latter dismounted, the receiver is left open straight through from the rear in the direct line of the axis of the barrel bore, so that the barrel and receiver may easily be cleaned from the rear, through their full lengths. Also, any of the parts 105 of the breech closure assembly, including the extractor and extractor spring, can be replaced practically instantaneously should such necessity arise.

Means is provided for manually operating 110

the breech closure. As best seen in Figs. 5, 6 and 8, the receiver has on one outer face, the right side as herein illustrated, the hand-action guide 98, of the general shape in 5 cross-section as shown in Fig. 5. The hand-action slide 99 works on this guide. In its normal inactive or rest position, at the forward end of its guide 98 it is also rotatable, through an angle of about 45°, to render it 10 inactive and hold it locked to the receiver, or to engage it operatively with the breech mechanism, herein through the gas fork. The latter has pivoted to it as by means of the hand-action lug 100, Figs. 18 and 20, the 15 hand-action slide link 101. At the rear end of the latter is a lateral wing 102. A lug 103 on the hand-action slide 99 is positioned to be engaged in front of this wing when the slide is turned down, that is, clockwise 20 facing the muzzle, by down movement of the hand-lever 104. In such "down" position the locking lugs 105 at the upper face of the hand-action slide are swung out from engagement in their retaining recesses 105^a in 25 the adjacent wall of the receiver. The hand slide is then free to be pulled back, to open the breech through engagement with the link 101 connected to the gas-fork. The lugs 105 are constructed and arranged to 30 ride along the adjacent portion of the receiver and of the guide 98, and to hold the hand lever in its down position once it has started its back movement, and until it returns to forward position serving also to 35 limit the turning movement of the slide and its hand-lever. Spring means 106 anchored to the receiver as at 107 is preferably provided automatically to restore the hand-lever to its normal "up" position as it returns 40 forwardly, said spring means engaging over and bearing down upon one offset lug 105 and turning the slide and hand lever reversely, herein upwardly, thus disengaging the slide and the link 101 and 45 locking the former in rest position.

It will be seen that the gas mechanism previously described is so arranged and that the hand-action mechanism is so related thereto, through the gas-fork, that the gun 50 may be used as a hand-operated weapon at any time, or if the gas mechanism should for any reason become disabled. In fact, the gun may be operated manually with all parts of the gas mechanism in advance of 55 the gas-fork and action-spring tube removed, if desired. During normal operation of the gun, however, the hand slide and hand lever remain at rest in out-of-the-way position, avoiding possibility of injuring 60 the operator from a constantly reciprocating hand-action.

Feed mechanism

Any preferred type of feed may be employed, such as a magazine with a spring 65

elevated follower therein, loaded from a clip which does not enter the magazine, as in the Springfield rifle, or a loader, clip or so-called packet feed whereby the cartridges are supplied in a loader or packet which is bodily placed in the magazine space and ejected therefrom when emptied of its cartridges, a feed type well known in the art and illustrated, for example, in the U. S. Patents 513,647 and 522,603 to James P. Lee. In the present instance I have shown a novel feed of this latter type. 70 75

As seen in Fig. 2, the magazine or feed housing 110 extends below the guard-plate 70, covering the feed opening therein, and is held by the master screw 11 previously mentioned. It is adapted to receive a loader or packet 112, see in detail in Figs. 21 and 22, inserted from above through the loading and loader-ejecting opening 113 in 80 85 the receiver; see Fig. 8.

Referring to said Figs. 21 and 22, a loader or packet 112 may contain any preferred number of cartridges, its capacity being ten, in staggered relation, in the form 90 illustrated. It comprises a light sheet metal casing including the forwardly converging side walls 114, 114, a rear wall 115 and the inturned cartridge retaining and guiding lips 116, 116 at both top and bottom. These lips are so disposed and the loader as a whole is so constructed that it may be inserted either end foremost, making it unnecessary for the operator to delay to distinguish as between top and bottom under the stress of service conditions. On the rear wall of the loader two oppositely inclined nibs 117, 117 are struck out, for alternative engagement below the nose 118 of the loader catch 119, to be more fully described. These nibs are likewise constructed and arranged to accommodate the above mentioned interchangeable positioning of the loader. Preferably the side walls of the loader or packet are formed 100 with vertical ribs 114^a, 114^a, for guiding engagement with the channelure of the cartridges. 105 110

Fixed to and resting upon the bottom wall of the magazine 110, Fig. 2, is a combined follower spring and packet-ejecting spring 120, seen separately in plan in Fig. 23. One portion of this spring is reversed upon itself to form a follower or cartridge-lifter spring 121, while the other portion or leaf 122 engages below one lip 116 of the packet 112, to eject the latter when emptied and released by manual operation of the packet catch 119. 115 120

The reversed leaf 121 of this spring 120 has its free end engaged beneath the forward part of the main lifter-arm 123 pivoted at 124, as upon the adjacent magazine wall. A stop 125 engageable with the guard plate 70 limits upward movement of 125 130

this lifter-arm. The lowermost cartridge seats upon a follower 126 formed as a finger pivoted at its rear end, as at 127 to the rear part of the lifter-arm 123. A spring 127a between these two parts assists in the feeding action, while the rear ends of the lifter-arm 123 and the follower 126 interengage to limit the upward movement of the latter.

It will be understood that the cartridges are fed upwardly in the loader or packet by the described spring follower or lifter of the magazine and are picked off alternately from the opposite sides of the loader, each topmost cartridge in turn being engaged and forced home into the firing chamber by the breech block. The loader and magazine are so located that the cartridges follow substantially a straight path during loading, with any necessary swinging or lift by the breech block reduced to the minimum. The magazine, and consequently the loader, is in such close proximity to the breech, the cartridge noses being scarcely one-third a cartridge-length to the rear thereof, that accurate travel of the loading cartridge is assured. The loader may accordingly be relatively short, facilitating the feeding engagement of the block with the cartridge and giving adequate clearance space for the operation of all parts.

Further to insure accurate feeding of the cartridges, particularly with a loader or packet as short as herein illustrated, I may employ a cartridge retaining and guiding device intermediate the packet and the breech, such as illustrated in Figs. 2, 4, 5, 18 and 24. As best seen in Figs. 2 and 18 a rearwardly facing yoke 128 is mounted at the upper forward portion of the feed chamber, as by means of a forward flange 128a secured to the receiver lug 10 by the master screw 11. Pivoted between the two legs of this yoke 128, as at 129, 129, Figs. 2 and 18, is a yieldable cartridge guide and retainer 130, also of general U-shape, having inwardly projecting lips 131, 131 at the rear of each leg, adapted to overlie and at times engage the uppermost cartridge. The cross-portion 130a of this guide at a point below the guide pivots 129, is in engagement with the rear end of the action-spring guide rod 32, which holds the guide 130 elevated substantially in the position of Fig. 2, its upward movement being limited by the stops 128b, 128b projecting inwardly from the two legs of the yoke 128 and overlying the respective legs of the guide 130.

The guide 130 is formed with sufficient lateral resiliency and its lips 131, 131 are so shaped and arranged that they are readily spread by the cartridges in the insertion of a fresh packet. In case it is desired to remove a packet while cartridges still remain in it, I preferably provide means for simi-

larly spreading these lips. Referring to Fig. 24, said means is illustrated as a manually depressible member 132, vertically movable in the stock, with its lower end in the plane of one leg of the guide 130. Its upper end projects slightly above the receiver, terminating in a finger piece 133 by which it may be pushed down, depressing the guide lips 131 and spreading them down over the uppermost cartridges. Release of the packet latch 119 will then allow the spring 120 to free or eject the packet with any cartridges therein.

Means is preferably employed whereby the breech is caught and held open when the last cartridge has been fed and fired. Accordingly, as seen in Figs. 2 and 3, I have provided a breech catch 135 formed as a forwardly extending lever having a depending arm or breech-catch release 137. At its rear end is a hub 138, see Fig. 14, by which it is supported for vertical rocking movement upon the striker stud 139, to be referred to more fully in connection with the firing mechanism.

The breech catch 135 normally lies below the path of the gas fork 28, by reason of its own weight and arrangement, but may be urged downwardly by a spring if desired. In the lower edge of one side or fork of the gas slide 28, herein the right fork, is a retaining notch 141, positioned to come vertically opposite this breech catch when the block and gas fork are in their rear or open position. So long as a cartridge remains in the loader, the breech catch stays down, as in Fig. 2, and the block automatically returns to closed position. But when the loader has been emptied of its last cartridge the breech catch is elevated into position to engage said retaining notch 141 of the gas slide, holding the block open. This elevation of the breech catch is herein effected through the medium of a lateral pin 142, Fig. 2, on the lifter arm 123. As the last cartridge is fed from the loader, this pin 142 moves up into engagement with a lateral projection 143 on the nose 144 at the upper end of the breech catch, forcing the latter upwardly and yieldingly holding it elevated, in readiness to snap into the retaining notch 141 of the gas fork as the latter comes back. The block is thus caught and held open, indicating the need for replenishment of the cartridge supply, in this case by the insertion of a fresh packet or loader.

With the breech thus automatically held open the loader may instantly be ejected from the magazine, by the spring portion 122 already described. To effect such ejection, the operator has but to push forward the finger-piece 145 of the loader catch 119, located at the rear of the magazine, immediately in advance of and convenient to a finger of the operator's hand in normal po-

sition on the gun. Upon release of this loader catch, the empty loader or packet is thrown from the gun instantly permitting a full loader to be inserted.

- 5 The loader catch 119, Figs. 2 and 25, is pivotally supported on the adjacent edge of the guard-plate 70 by means of its rearwardly facing fulcrum-slot 146, the top and bottom walls of which limit its motion. It 10 is urged forwardly, into loader-holding position as in Fig. 2, by the spring 147 housed in the body of the catch. The catch as a whole is held in position, as best seen in said Fig. 25, by a lateral projection 148 on the 15 base 69 of the ejector 68, previously described, this projection extending across directly in front of the catch. The ejector thus has the additional function of positioning the loader catch.
- 20 It may now be observed, referring particularly to Fig. 2, that upon dismounting the receiver and breech closure assembly, which requires only the removal of the strap 7 and the master screw 11, and upon removing 25 the firing or lock mechanism, the latter a unitary assembly to be described, there then remain on the stock, of the parts described, only the guard-plate 70, the ejector 68, the loader catch 119 and the stock-abutment 92 holding the receiver-cap latch 90. It will rarely be desirable to dismount any 30 of these parts, but this may easily be done, as removal of the ejector frees the loader catch, whereupon the guard-plate and stock abutment may be taken down, by mere removal of the bolt 97, the adjacent screw 96, and the screw 149 at the fore end of the 35 guard-plate.

The open breech closure may be returned 40 to its closed position of Fig. 2 at any time, before or after insertion of a fresh loader, by rearward movement of the breech-catch release 137, Figs. 2 and 3, sufficient to draw down the breech catch 135 from its retaining notch 141 in the gas fork. The gas fork and breech closure are thereupon carried forward into closed and locked position by the return expansion of the action spring 30. The breech-catch release 137 extends 45 below the guard-plate 70 adjacent the magazine 110 and convenient to the operator's hand.

Firing or trigger mechanism

- 55 The firing or trigger mechanism is a unitary assembly which, together with the breech catch already described, may readily be positioned or dismounted as a separate unit. It comprises a striker frame 150 formed to seat on the underlying platform portion 3a of the stock, Fig. 2, being held by the bolts 151, 151 extending up through the guard plate 70. Referring to Figs. 2, 60 13 and 14, the striker or firing-pin ham-

mer 152 is pivoted on the stud 139 at the fore part of the striker frame, this stud being extended at both sides of the frame to form, at the right side, the pivot for the breech catch 135, as previously mentioned, and, at the left side, the pivot for the disconnector lever 182, described below. The striker has a head 154 of sufficient mass to insure the detonation of a cartridge primer even where the latter is relatively heavy and difficult to indent. An anvil 155 is formed at its front face at the proper point for engagement with the butt 82 of the firing pin 80. If desired, and as shown, a roller 156 may be mounted on the striker head, to insure easy action between the striker and the under face of the block, but has been found unnecessary in practice.

Referring to Figs. 13 and 14, and as also seen in Figs. 2 and 3, the striker 152 is provided with a cocking notch 157 at its lower end for receiving the nose 158 of the sear 159, the latter an elongated member hung at its rear end on a pivot pin 160 in the striker frame. The parts are shown in their cocked position in Fig. 2 and in fired position in Fig. 13. The striker is cocked against the action of a spring unit comprising the striker spring 161 surrounding a rod 162 having a forked head 163 pivoted to the striker at 164, this rod being slidably supported at its rear end in a lug 165 at the upper face of the sear 159. For additional convenience in assembling, and also to provide for a certain desirable amount of play or back movement of the striker from its fired position before the spring is compressed, I preferably employ a spring-retainer or housing 166, seen in Figs. 2 and 13 and separately in Fig. 15, a sheet metal 105 clip-like device having an apertured foot 167 at each end, and having intermediate spring-enclosing side flanges 168, 168. At the forward end of the spring guide-rod 162 is a sleeve 169, free to slide on the rod, and having a collar 170 at its rear end which forms the front abutment for the striker spring. The latter bears at its rear end against the rear foot 167 of the spring-retainer, which abuts the lug 165 on the sear. 110

By reason of this spring-retainer 166, the striker spring remains in place upon its guide rod, in disassembling the elements of the firing mechanism unit. It may readily be slipped off the rod, if desired, together with the sleeve 169 and the spring-retainer, these three parts retaining their relative position, as in Fig. 15, ready to be slipped back onto the guide rod. It will be noted that the forward action of the spring, to swing the striker against the firing pin, is through the sleeve 169, the latter abutting the rod head 163. The collar 170 of this sleeve brings up against the front foot 167 of the spring-retainer, allowing the striker to com- 125 130

plete the last fraction of its firing movement under its acquired momentum. Similarly, after firing, the striker and the rod 162 have a free back movement over the same limited distance, until the rod head 163 again engages the front end of the sleeve 169. This action compensates for any recoil of the firing-pin relative to the block, and also provides an efficient buffering of the striker itself, through the striker spring.

This spring 161 serves not only as the striker spring and buffer but also as the sear spring, holding the sear nose 158 up against the under face of the striker hub during the firing and cocking movement thereof, in readiness to snap into the cocking-notch 157.

Release of the sear, to fire the rifle, is controlled through the depending sear tail 172. In the cocked and ready position of the parts, Fig. 2, the sear tail is engaged in a notch 173 at the rear of a disconnector or dog 174, seen separately in Fig. 16, pivoted at 175 on the shank 176 of the trigger 177.

A coil spring 178 seated in recesses in the step 179 of the trigger and bearing upwardly against the disconnector, urges the latter upwardly into engagement with the sear, as in Fig. 2. The trigger is pivotally suspended at the upper end of its shank 176 on a pivot pin 180 in the striker frame 150. It is urged forwardly and downwardly by the trigger-spring 181 seated in the trigger shank and bearing upwardly against the overlying portion of the striker frame 150.

Through the medium of the disconnector 174 provision is made whereby the trigger cannot move the sear to release the striker until the breech is completely closed and the block locked, although firing cannot in any event occur until the block is so positioned, as the firing pin is not until then in line with the primer. To this end, I employ the disconnector lever 182, previously referred to, having a hub 183 rockably supported on the left end portion of the striker stud 139, as previously stated, see Fig. 14, and a forward arm or depressor 184. A suitable spring, herein the leaf spring 185, best seen in Figs 3 and 14, is fixed at its fore end to the rear hub portion of this disconnector lever as by the screw 186, while its rear end is held under tension beneath a pin 187 of the striker frame, so that the spring exerts a down pressure at its fore end, urging the forward arm 184 of the disconnector upwardly and its rear arm 182 downwardly, out of engagement with the under or cam face 188 of a forwardly projecting nib 189 on the disconnector 174, Fig. 16.

The tip of the forward arm 184 of the disconnector lever is thus positioned in the path of a cam surface 190 at the lower rear end 65 of one fork, herein the left fork, of the ac-

tion-slide or gas fork 28. When the latter is in its full forward position and the breech is consequently closed and locked, the fore end of the disconnector lever is up, behind said cam surface 190 on the gas fork, 70 and its rear end is down, out of engagement with the disconnector and allowing the latter to engage the sear tail. But when the gun is fired and the gas fork moves back, the latter depresses the fore end of the disconnector and elevates its rear end. Thus the rear arm of the disconnector lever is brought up into engagement with the nib 189 of the disconnector, tipping the sear-engaging notch therein downwardly to such point below the sear tail that pull on the trigger can have no effect on the sear. The disconnector lever remains in its trigger and sear disconnecting position during movement of the gas fork in either direction, and so long as the latter is in any other than full-forward breech-closing position, making it impossible to fire the gun unless the breech is closed and locked.

The disconnector 174 also functions to prevent unintentional "repeats". After each shot, the trigger must be released and allowed to come forward, else the disconnector is out of position to engage and operate the sear.

It will be noted that the firing mechanism contains but six working parts, including the striker, striker spring guide-rod, sear, disconnector, disconnector lever and trigger, all of rugged construction and all bodily contained as a unit in the striker frame 150.

Safety

Additional safety mechanism is desirably provided, herein associated with the disconnector 174 and with the sear. The disconnector, as seen in detail in Fig. 16, has a forwardly projecting finger 191 with an under surface adapted to be engaged by an inclined cam portion 192, see Fig. 17, of a safety pin 193 extending transversely through and slidably supported in the stock.

The safety pin has a flat-topped recess 194 in its under side, by which it is guided on a portion of the guard-plate 70, the end walls of this recess limiting the movement of the pin. It is yieldingly held in "safe" or in "firing" position by a spring-pressed detent 195 engageable in recesses 196, 196 in the guard-plate.

In Fig. 17, which is taken looking forwardly, the safety is in firing position, the low part of the inclined cam portion 192 being opposite the disconnector finger 191. In this position a notch 197 in the top of the safety pin is directly below a locking-piece 198 depending from the sear, permitting the latter to be moved to release the striker. If the safety pin is pushed axially to the right, Fig. 17, the cam portion 192 130

slides up under the disconnector finger 191, swinging the latter upwardly and carrying the sear notch to a level below the tail of the sear, in a similar manner as is done by 5 the action of the disconnector lever 182 when the breech is open. Simultaneously the notch 197 in the safety pin is moved out of the plane of the locking-piece 198 of the sear, which accordingly is positively 10 locked up. If it is in striker-cocking position, it cannot be moved to release the striker. Thus the rifle can be carried cocked and with a cartridge in the firing chamber, with absolute safety. It cannot be fired by 15 pull on the trigger, and is positively locked against firing by jarring or otherwise.

It will be seen in Fig. 17 that the safety pin projects at the left side of the gun when in "firing" position, but, when in the "safe- 20 ty" position, its other and right end, which must then be pushed in in order to release the safety, is concealed in a depression 199 in the stock. For this reason the safety cannot readily be unintentionally released; 25 on the other hand, it will be automatically applied by the weight of the gun itself, if the latter is laid upon its left side, the normal way for a man to lay a gun down. If desired, the two ends of the safety member 30 193 may additionally be differentiated by coloring them distinctively and/or by word marking.

My invention is not limited to the particular embodiment shown and described herein, its scope being set forth in the following 35 claims:

I claim:

1. In a gun, a receiver, a pair of action plates reciprocable therein, a reciprocable 40 breech block between said plates, the latter having opposed lateral cam formations operatively connecting them with the breech block and providing for relative transverse movement between them and the block, and 45 a gas-operated actuator element removably connected to each action plate symmetrically.

2. In a gun, a receiver, a breech block movable longitudinally and also transversely therein, a reciprocating action-plate along 50 a longitudinal face of the breech block and at least partly housed therein to form a unit assembly with the breech block, said action plate being operatively connected to the breech block for effecting the movements 55 thereof, and a gas-operated spring-returned element for reciprocating said action plate.

3. In a rifle, in combination, a receiver, a block non-rotatably slidably therein, a plurality of locking lugs symmetrically dis- 60 posed on the block, a corresponding plurality of abutments on the receiver, action plates set in the sides of the block, slidably guided in the receiver and having 45°-angled rib-and-slot connection with the block, and 65 a gas-operated actuator removably engaging

the action plates, whereby the block is reciprocated longitudinally and moved transversely to bring its lugs into and out of locking engagement with the receiver abutments. 70

4. In an automatic gun, in combination with a barrel, a receiver and a non-rotary block slidable therein and also transversely movable to locked or unlocked position, an action plate adjoining and having rib-and-slot connection with the block at an angle of approximately 45° to the axis of the bore, a gas-operable slide removably connected to the plate, a gas piston having operative engagement with the gas slide and containing a gas expansion chamber, and means to admit gas to said chamber from the barrel. 75

5. In an automatic gun having a receiver and a breech block movable to forward, locked position and to retracted position therein, gas-operating means for the block including a gas tube, a gas piston slidable therein, and a gas-slide operatively associated with the piston, and one or more action plates intermediate the gas-slide and breech block, said plate or plates being readily disengageable from the gas-slide and associated with and at least partly housed in the block for removal or insertion therewith as a unit. 80

6. A firearm of the class described, comprising a receiver, a barrel, a breech bolt cooperative therewith and equipped with operating mechanism, a rearwardly directed inclined engaging face on a portion of said mechanism, and a buffer consisting in a relatively heavy spring metal member presenting a similarly inclined engaging face to that of said operating mechanism, said buffer member being secured to the receiver but with its face-presenting portion left free to yield transversely when engaged by said engaging face of the operating mechanism. 90

7. A firearm of the class described, comprising a barrel, a breech bolt mounted for opening and closing movement with respect to said barrel, a packet for holding the rear portions of cartridges to be fed, a packet chamber, means for feeding cartridges from said packet, and yieldable means intermediate a positioned packet and the barrel breech and overlying the upper-most cartridge in a packet to guide it during its forward feeding movement from the packet. 100

8. A firearm of the class described, comprising a barrel, a breech bolt mounted for opening and closing movement with respect to said barrel, a packet for holding the rear portions of cartridges to be fed, a packet chamber, means for feeding cartridges from said packet, yieldable means intermediate a positioned packet and the barrel breech and overlying the upper-most cartridge in a packet to guide it during its forward feeding movement from the packet, and manual 110

means to move said guide means to inoperative position for removal of a loaded or partly loaded packet from its chamber.

9. In a firearm, in combination, a receiver, 5 a barrel, a reciprocating breech-bolt for the barrel, an automatically actuated, reciprocating member for controlling and operating the breech-bolt, a manual lever whereby with to operate said member, said lever slidably supported on the receiver and being also movable into an operatively engaged position or into a normal disengaged position wherein it remains at rest during automatic operation of the firearm, and means 10 positively locking said lever against sliding movement when in its disengaged position.
10. In a firearm of the character described, in combination a breech block, a member for controlling and operating the 15 block, said member being rectilinearly slidable in parallelism with the axis of the bore and having its major portion above said axis, a receiver with which the block is locked in firing position, and a gas-controlled actuator removably connected to the lower portion of said member, operating automatically to pull the block transversely toward itself to unlock the block from the receiver and thereafter to move it rearwardly to open 20 the breech.

11. A firearm of the character described, having, in combination, a breech block supported for longitudinal opening and closing movement and also for transverse movement 35 to lock and unlock it, an action-plate positioned flatwise along one longitudinal face of the block and having cam and groove connection therewith, said action-plate being longitudinally movable but restrained 40 from transverse movement, and a gas-operated actuator separably connected to said action-plate, said action-plate and block having a longitudinal opening and closing movement in unison, and said plate having 45 an additional longitudinal movement relative to the block during which it effects the transverse locking or unlocking of the latter.

12. In a firearm, a barrel, a receiver therefor, a reciprocable breech block, a gas-operable actuator including a piston, a tubular action-spring housing rearwardly thereof and a fork or saddle portion adapted to straddle the feed chamber, guide means on 55 the receiver for said fork or saddle portion, action-plates at opposite vertical longitudinal sides of the block, and having cam and groove connection therewith, means on the receiver to guide said action-plates longitudinally and to prevent vertical movement thereof, and lugs and recesses therefor 60 separably connecting the fork or saddle and said action-plates.

13. In a firearm, a reciprocating breech 65 block, an extractor movably mounted at the

fore end of the block, a substantially flat extractor spring along one face of the block yieldingly holding the extractor in cartridge-engaging position, a firing pin movable in a bore in the block, and common 70 means for securing the extractor spring in position and for confining the firing pin in the block.

14. In a firearm, a reciprocating breech block, an extractor, a spring therefor one 75 or more vertical recesses in the block adjacent the rear end of the spring, and a like number of depending members on the spring, receivable in the respective recesses, and engageable with the firing pin to limit 80 the lengthwise movement thereof.

15. In a firearm, a reciprocating breech block, an extractor carried by the breech block, including a horizontal portion adapted to seat in a recess in the upper face 85 of the block and a cartridge-engaging toe at the front face of the block, cooperating rib-and-groove formations on the extractor and the block providing for relative vertical sliding movement between them and also 90 a slight rocking movement of the extractor, and spring means tending to hold the extractor in normal position on the block.

16. In a firearm, a reciprocating breech block, an extractor carried by the breech 95 block, including a horizontal portion adapted to seat in a recess in the upper face of the block and a cartridge-engaging toe at the front face of the block, cooperating 100 guide formations on the extractor and the block, providing for relative vertical movement between them, and a spring tending to depress the extractor with respect to the block, said spring having two portions respectively engaging laterally spaced points 105 of the extractor, each such portion being functionally sufficient by itself.

17. A cartridge-holding loader or packet for reception in a firearm comprising a sheet metal member of U-shape in cross section, including a rear wall and relatively short convergent side walls, and similar cartridge-retaining lips at both the top and the bottom of the side walls, the rear wall having two oppositely disposed ribs, one 110 above the horizontal center line of the rear wall and offset from the vertical median line, and the other a similar distance below said horizontal center line and equally offset to the other side of said vertical median line, for alternate engagement by the same holding instrumentality of a gun, whereby the loader may be inserted either end foremost and be retained by said single holding instrumentality.

18. In a gun of the class described, a reciprocable breech block, a magazine or feed chamber below the path of the block, a cartridge loader or packet receivable in the magazine, cartridge-lifting means in the 115 120 125 130

magazine for feeding the cartridges successively from the loader or packet into position ahead of the open block and common spring means for operating the lifting means and for ejecting an empty packet or loader.

19. In a gun of the class described, a reciprocable breech closure including a block and operating means therefor, a magazine below the path of the block, a cartridge loader or packet receivable in the magazine, lifter means to feed cartridges from the loader into the path of the block, a normally inoperative breech catch to hold the closure open, means to position the breech catch for holding engagement with the closure when the last cartridge has been fed out of the loader or packet, manually controlled means to eject the empty loader or packet at the will of the operator, and other independent manual means to release the breech catch.

20. In a gun of the class described, reciprocating breech closure mechanism, including a firing pin, a striker, a frame pivotally supporting the striker, a trigger pivoted on said frame, a sear pivoted on said frame to the rear of the striker and trigger pivots for holding the striker cocked or releasing the same, a disconnector element between the sear and trigger and pivoted on the latter for operatively connecting or disconnecting them, and means controlled by the breech closure mechanism for placing said disconnector element in disconnecting position so long as the breech is open.

21. In a gun of the class described, a reciprocating breech block carrying a firing pin, an actuator for the breech block, firing mechanism including a pivoted striker, a sear and a trigger, a disconnector operatively interposed between the sear and trigger and bodily pivotally supported on and by the latter, and a disconnector lever engageable by said actuator to move the disconnector to sear-and-trigger-disconnecting position and so retain it during opening and closing of the breech.

22. In a gun of the class described, reciprocating breech closure mechanism, including a firing pin, a pivoted striker, a sear for holding the striker cocked or releasing the same, a trigger, a disconnector element between the sear and trigger for operatively connecting or disconnecting them, means pivoted coaxially with the striker and controlled by the breech closure mechanism for placing said disconnector element in disconnecting position so long as the breech is open, and other means similarly to control said disconnector element manually for safety purposes.

23. In a gun of the class described, reciprocating breech closure mechanism, including a firing pin, a striker, a sear for

holding the striker cocked or releasing the same, a trigger, a disconnector pivotally mounted on the trigger and operatively interposed between the sear and trigger for operatively connecting or disconnecting them, a pivoted disconnector lever, a breech catch, and a firing-mechanism frame wherein said striker, sear, trigger, disconnector lever and breech catch are each pivotally mounted for removal and assembly therewith as a unit.

24. In a gun of the class described, reciprocating breech closure mechanism, including a firing pin, a striker, a sear for holding the striker cocked or releasing the same, a trigger, a disconnector element between the sear and trigger for operatively connecting or disconnecting them, safety means for moving said disconnector element to and holding it in disconnecting position, and for simultaneously locking the sear in striker-cocking position.

25. In a gun of the class described, a reciprocating breech block, firing mechanism including a firing pin, a striker, a sear for the latter, and a trigger, a safety device for operatively connecting or disconnecting the sear and the trigger and/or for locking the sear and the striker in cocking relation, said device including an operating portion projecting externally laterally beyond adjacent parts when it is in non-safe position and adapted to be actuated by the weight of the gun itself thereby automatically to apply the safety when the gun is laid upon a given side.

26. In a gun of the class described, in combination with a reciprocating breech block having a firing pin, a lock or firing mechanism assembly adapted to be mounted or dismounted as a unit, said assembly comprising a striker frame, a striker pivoted thereon, a sear movable on the frame, spring means actuating the striker and also urging the sear to cocking engagement with the latter, a trigger pivoted on the frame, and a pivoted element operatively intermediate the sear and trigger to connect or disconnect the same.

27. In a gun of the class described, in combination with a reciprocating breech block having a firing pin, a lock or firing mechanism assembly adapted to be mounted or dismounted as a unit, said assembly comprising a striker frame, a striker pivoted thereon, a sear pivoted on the frame, spring means actuating the striker and also urging the sear to cocking engagement with the latter, a trigger pivoted on the frame, a pivoted element operatively intermediate the sear and trigger to connect or disconnect the same, and an automatic disconnector lever pivoted coaxially with the striker.

28. In a gun of the class described, in combination with a reciprocating breech

block having a firing pin, a lock or firing mechanism assembly adapted to be mounted or dismounted as a unit, said assembly comprising a striker frame, a striker movable thereon, a sear pivoted on the frame, spring means actuating the striker and also urging the sear to cocking engagement with the latter, a trigger pivoted on the frame, a pivoted element operatively intermediate the sear 5 and trigger to connect or disconnect the same, and a breech catch pivoted adjacent the striker.

29. In a firing mechanism for a gun of the class described, a pivoted striker, a finger-like sear pivoted near its rear end and engageable at its fore end with the striker to cock the same, an apertured lug on the sear spaced vertically from the sear pivot, a rod pivoted to the striker at one 10 end and slidably received in the aperture in said lug on the sear, and a coil spring on said rod and acting in one direction to move the striker to fired position and in the other direction to urge the sear into cocking engagement with the striker.

30. In a firing mechanism for a gun of the class described, a pivoted striker, a spring-guiding rod pivoted at one end to the striker, means slidably supporting the rod adjacent 15 its other end, a spring surrounding the rod, and a spring retainer including a spring-holding portion and end flanges through which said rod extends and between which the spring is held under compression, facilitating the assembling and disassembling of 20 the striker and related parts.

31. In a firing mechanism for a gun of the class described, a pivoted striker, a spring-guiding rod pivoted at one end to the 25 striker, means slidably supporting the rod adjacent its other end, a spring surrounding the rod, a spring retainer including a spring-holding portion and end flanges through 30 which said rod extends, and a sleeve slidably mounted in the rod aperture of the front flange, and adapted to engage a shoulder on the rod with its front end and to provide a front bearing for the spring at 35 its rear end, said spring bearing at its other end against the rear flange of the retainer.

32. In a gun of the class described, a barrel, a receiver therefor, a breech-closure unit including a reciprocating block carrying a firing pin, an extractor and extractor spring 40 and one or more action-plates, a receiver cap pivoted at the upper intermediate portion of the receiver and adapted to close-in the rear portion thereof, said breech-closure unit being bodily removable from the receiver in 45 the open position of said cap, the receiver and barrel being then wholly exposed at the rear in direct prolongation of the axis of the bore, for cleaning and inspection purposes.

33. In a firearm, a reciprocating breech 50 block, an extractor including a portion seat-

ing in a longitudinal face of the block and a cartridge-engaging toe at the front face of the block, and cooperating rib-and-groove formations on the extractor and the block providing for relative transverse sliding 70 movement between them and also a slight rocking movement of the extractor.

34. In a firing mechanism for a gun of the class described, a pivoted striker, a pivoted sear engageable with the striker to cock 75 the same, the sear having an apertured portion spaced transversely from the sear pivot, a rod pivoted to the striker at one end and slidably received in said apertured portion of the sear, and a coil spring on said rod 80 acting to move the striker to fired position and to urge the sear into cocking engagement with the striker.

35. In combination, in a gun having a receiver, a breech block reciprocable in the receiver, a firing pin movable in the block, extractor mechanism carried by the block and including an extractor proper and an extractor spring, a transverse recess in the block, and transversely extending means on the 90 rear portion of said extractor mechanism, said means received in said recess and cooperating with the firing pin to limit movement thereof.

In testimony whereof, I have signed my 95 name to this specification.

JOSEPH C. WHITE.
